UNITED STATES PATENT OFFICE.

JOSEF HERZOG, OF UNION, NEW JERSEY.

SHOE-CLEANING APPARATUS.

No. 895,458.

Specification of Letters Patent. Patented Aug. 11, 1908.

Application filed December 10, 1907. Serial No. 405,354.

To all whom it may concern:

Be it known that I, JOSEF HERZOG, a citizen of Austria, residing at the town of Union, Hudson county, State of New Jersey, have 5 invented new and useful Improvements in Shoe-Cleaning Apparatus, of which the following is a specification.

This invention relates to an apparatus designed to be placed near the entrance of a 10 house, hall or room, and adapted to effectively remove the soil from the sole, sides and top of a shoe.

In the accompanying drawing: Figure 1 is a side elevation of my improved shoe-cleaning apparatus; Fig. 2 a front elevation thereof; Fig. 3 a longitudinal section on line 3—3, Fig. 2; Fig. 4 a cross section on line 4—4, Fig. 3; Fig. 5 a similar section on line 5—5, Fig. 3, and Fig. 6 a plan.

20 A pair of parallel side plates 10, are connected at intervals by a series of fixed upwardly-directed brushes 11, arranged in a common horizontal plane and adapted to clean the sole of a shoe. Between brushes 11 25 are fitted a number of scrapers 12 which are set slightly beneath the tops of the brushes, so as to engage the sole when the foot is lowered. A drawer 13 guided in grooves 14 of side plates 10, beneath brushes 11 and scrapers 30 12, receives the soil which is free to fall into the drawer through the interstices between the brushes.

Above brushes 11, side plates 10 are provided with bristles 15 to constitute a pair of 35 facing upright brushes for cleaning the sides of the shoe. The bristles of these brushes with the exception of the front row, (Fig. 2) are reduced in length from the top downwards, (Fig. 5), so as to conform to the con- 40 tour of the shoe.

Back of the bottom and side brushes, there is provided a vertically movable concave cross-head 16 having downwardly projecting cross-bristles 17 to constitute a top brush. Cross-head 16 is provided with end flanges 18, guided in top slots 19 of side plates 10. Flanges 18 are perforated for the reception of upright rods 20, passing through perforations of side plates 10 and connected at their 50 lower ends to a vertically movable brush 21. This brush is set in advance of brushes 11, so

as to engage the tip of the sole and is guided in bottom notches 22 of side plates 10. Brush 21 is normally suspended somewhat higher than brushes 11, and its upwardly- 55 directed bristles are stepped, (Fig. 3), so that as the foot is advanced, brush 21 will be gradually depressed to the level of brushes 11. Rods 20 are encompassed by coiled springs 23 interposed between flanges 18 of 60 cross-head 16 and an abutment 24 of side plates 10. The upper threaded ends of rods 20 are engaged by threaded caps 25 that bear upon flanges 18 and permit the tension of springs 23 to be adjusted. As the foot is advanced, it will depress sliding brush 21, and the latter will, by rods 20 and caps 25, draw cross-head 16 down, so that the bristles 17 65 will be firmly forced against the top of the shoe. This engagement is maintained as 70 long as brush 21 is held in its lowered position by the foot. As soon as the latter is withdrawn, cross-head 16 will be raised by springs 23, ready for the next operation.

It will be seen that in my apparatus the 75 brushes are adapted to snugly embrace the shoes, so that the latter may be quickly and effectively cleaned.

I claim:

1. A shoe cleaning apparatus, comprising 80 a pair of side plates, a vertically movable bottom brush, rods projecting upwardly therefrom, a vertically movable top brush having perforations for the reception of the rods, caps on the rods that engage the top 85 brush, and springs interposed between the side plates and the top brush, substantially as specified.

2. A shoe cleaning apparatus comprising a 90 fixed bottom brush, a movable bottom brush, a movable top brush, means for connecting the movable bottom brush to the top brush, and means for normally sustaining the movable bottom brush above the fixed bottom brush, substantially as specified. 95

Signed by me at New York city, (Manhattan,) N. Y., this 9th day of December, 1907.

JOSEF HERZOG.
